UNITED STATES PATENT OFFICE.

HENRY C. STEFFENS, OF SAN FRANCISCO, CALIFORNIA.

ELECTRIC PERFORATING MACHINE.

Application filed February 9, 1924. Serial No. 691,863.

This invention relates to a perforating machine, and particularly to a machine whereby paper stencils may be traced upon and perforated by an electric spark.

5 The object of the present invention is to generally improve and simplify the construction and operation of electric perforating machines; to provide means for increasing or decreasing the intensity or current of 10 the spark so as to produce perforations both fine, intermediate and coarse; to provide a pencil whereby tracing and perforation are simultaneously accomplished, and further, 15 to provide means whereby the circuit through the pencil and the machine is automatically closed when the pencil is employed, and conversely opened when the pencil is laid down.

One form which my invention may assume 20 is exemplified in the following description and illustrated in the accompanying drawings, in which—

Fig. 1 is a diagrammatic view showing the electric circuits employed in the perforating machine.

Fig. 2 is a longitudinal sectional view of the pencil.

Referring to the drawings in detail, and particularly to Fig. 1, A indicates, in general, a transformer, the primary winding 2 of which is connected with a suitable source of alternating current supply through wires 3 and 4. Interposed between the wire 4 and the primary winding of the transformer is 35 an incandescent bulb 5 which is employed as a resistance, and connected therewith is a switch 6. The wire 4 is connected to the terminal 7 of the bulb and this terminal is in turn connected through a wire 8 with one 40 contact 9 of the switch. The other terminal of the bulb is connected through a wire 10 with the opposite terminal of the switch and the main terminal of the switch is connected through a wire 11 with one side of the primary winding. If the switch lever engages 45 the contact 9, no resistance is imposed on the circuit as the current will pass through the wires 4, 8 and 11, but if the switch is thrown into engagement with the opposite contact, 50 the current will pass through the bulb, the wire 10 and the wire 11, thus imposing a predetermined amount of resistance.

The secondary winding of the transformer indicated at 12 is connected at one end 55 through a wire 13 with a switch 14. The other terminal of the secondary winding is

connected through a wire 15 with a grounding plate 16. A condenser of suitable capacity indicated at 17 is connected between the wires 15 and 13 and a resistance in the 60 form of an incandescent bulb such as indicated at 18 is also imposed on the secondary circuit.

The apparatus here illustrated perforates paper and like materials by means of an 65 electric spark action and a pencil generally indicated at B is employed in connection with the grounding plate 16 for this purpose. The pencil may be of any suitable shape, but it is in this instance cylindrical 70 and elongated. It consists of a tube or rod of insulating material such as indicated at 19 through the center portion of which extends a conductor or rod 20. The upper end 75 of the pencil contains a bulb 21 which is partially filled with mercury as indicated at 22. The bulb is provided with two terminals, a central rod like terminal 23 extending downwardly into the bulb, and an end terminal such as indicated at 24. The central rod terminal 23 is connected through a wire 25 with one end of the primary winding of 80 the transformer. The end terminal 24 is connected directly to the wire 3. The main terminal of the pencil indicated at 20 is connected through a wire 26 with one contact 27 of the switch 14. This same contact is connected by means of a wire 28 with one terminal of the bulb 18. The other terminal of the bulb is connected through a wire 29 with the opposite contact of the switch, 85 and the main terminal of the switch is connected through the wire 13 with one end of the secondary winding 12 of the transformer. 90

The bulb 21 containing the mercury and the two contacts 23 and 24 serve as an automatic switch. If the pencil is grasped and held in an inclined or vertical position, the mercury runs down to the end of the bulb and as such closes a circuit between the terminals or contacts 23 and 24. This in turn closes the circuit through the primary winding of the transformer. This circuit can be 95 traced as follows:

The alternating current coming in on the wire 3 passes through the contact 24, the mercury 22 and the second contact 23. It then passes through the wire 25, the primary winding 2, then through wire 11, switch 6, contact 9, wire 8, and finally passes 100 out through the main feed wire 4; that is, 110

it takes this circuit if the switch lever in switch 6 is thrown into engagement with contact 9, but if a resistance is desired, the circuit passes through wire 11 and the opposite contact, then through wire 10 and the bulb and finally out through the wire 4, the circuit passing through wire 8 when no resistance is desired and through wire 10 and the bulb when resistance is required.

10 The secondary circuit is established when the main terminal of the pencil indicated at 20 is brought into contact with the grounding plate 16. This circuit can be traced as follows:

15 The current from the secondary winding in the condenser passes out through wire 13 to the switch 14. If no resistance is required, the switch lever engages contact 27 and the current will thus pass through the 20 wire 26, the rod terminal 20, plate 16, and it will then return on the wire 15 to the secondary winding and the condenser. If resistance is desired, the switch lever is thrown into engagement with the opposite contact of 25 the switch 14. The current will then pass through the wire 29, bulb 18 and wires 28 and 26.

30 In actual operation if it is desired to make a perforated tracing of a stencil, figure, design or otherwise, it is only necessary to place the original on top of the grounding plate 16. A sheet of transparent paper is then placed on top of the object to be traced and the pencil terminal 20 is then traced 35 over the lines appearing through the paper. If fine perforations are desired, both resistances, to-wit, bulbs 5 and 18, are employed. If an intermediate sized perforation is desired, one or the other of the bulbs may be 40 cut out, and if a coarse perforation is required, both bulbs are cut out of the circuit so as to impose no resistance.

45 Two or three sheets and often more may be perforated at one time by merely placing one on top of the other and, as this is the case, it can readily be seen that means must be employed for varying the intensity of the current or the spark produced, this being accomplished as previously stated by employing 50 one or more resistances as illustrated.

55 While the apparatus here shown is more or less specifically illustrated, I wish it understood that various changes in form and proportion may be resorted to within the scope of the appended claims. I similarly wish it understood that the materials and finish of the several parts employed may be such as the experience and judgment of the manufacturer may dictate or various uses 60 may demand.

While the apparatus here illustrated has been described as a tracing and perforating

device for making stencils or the like, I wish it understood that it may also be employed for the purpose of signing checks and for 65 perforating the same. Where it is desired to perforate a check it is possible to employ an electrode which is provided with a flat straight edge. This edge when drawn over a check will perforate it in innumerable 70 places, and if a duplicate check is disposed below the same, one will serve as a duplicate for purposes of comparison to prevent fraud, etc.

Having thus described my invention, what 75 I claim and desire to secure by Letters Patent is—

1. An electric perforating apparatus comprising a bed plate adapted to receive paper sheets to be traced and perforated, an electrode-pencil for tracing and perforation, a transformer, the primary winding of said transformer adapted to be connected with a source of alternating current supply, a secondary winding in the transformer, one terminal of the secondary winding being connected with the bed plate and the other terminal of the secondary winding being connected to the electrode-pencil, a condenser connected between the terminals of the secondary winding, a resistance placed in the secondary circuit of the transformer, and a switch for throwing said resistance into or out of operation. 90

2. An electric perforating apparatus comprising a bed plate adapted to receive paper sheets to be traced and perforated, an electrode-pencil for tracing and perforation, a transformer, the primary winding of said transformer adapted to be connected with a 100 source of alternating current supply, a secondary winding in the transformer, one terminal of the secondary winding being connected with the bed plate, and the other terminal of the secondary winding being connected to the electrode-pencil, a condenser connected between the terminals of the secondary winding, and a mercury switch in the electrode-pencil and interposed in the alternating current circuit of the primary winding, said switch automatically closing a circuit through the primary winding when the pencil assumes a vertical or a substantially vertical position, and automatically opening the circuit when the pencil is laid flat. 105

3. In an apparatus of the character described, a transformer having a primary and a secondary winding, a bed plate, a pencil-electrode cooperating therewith, said pencil being connected both with the primary and the secondary winding of the transformer, and controlling the current flow through both. 110
